[57] **ABSTRACT**

Forming a sand mould prior to centrifugally casting a cast iron pipe by locating a mould containing flask against a sand blow head, bringing a plate against the other end of the flask and passing a mandrel having an oversized head through the plate and locating one end of the mandrel against the blow head, blowing sand into the annulus so formed between the mandrel and flask, compacting the sand at each end of the flask and compacting the remainder of the sand by withdrawing the mandrel from the flask so that the head of the mandrel effects the compacting.

METHOD OF AND APPARATUS FOR FORMING A SAND MOULD FOR USE IN THE MANUFACTURE OF A CAST IRON PIPE

This invention relates to a method of and apparatus for forming a sand mould for use in the manufacture of a cast iron pipe. Such pipe is subsequently manufactured by spinning molten metal within the sand mould so formed.

The technique of forming cast iron pipes by spinning molten metal within a preformed sand mould has been known for many years and is sometimes called "centrifugal casting". The sand mould is formed within a tubular enclosure normally known as a flask. Such a flask is open at both ends and these ends are closed while the sand mould is being formed. The moulded sand is then retained within the flask during the formation of the pipe. When the pipe is formed, it is removed from its flask and the sand may then be reused to form another mould.

In order to form a hollow interior to the sand mould, a mandrel is inserted to lie axially within the flask and this mandrel remains in position while the sand is being blown into the annulus between the mandrel and the flask. The mandrel is then withdrawn from the flask leaving the moulded sand ready to receive the molten metal at a subsequent stage in the process of forming the cast iron pipe.

Although the sand is blown under pressure into the annulus between the mandrel and the flask, in order to provide an accurately dimensioned cast iron pipe it is necessary to compact the sand so as to avoid the surface of the mould from being disrupted by the molten metal. This compacting of the sand has previously been accomplished by providing closure members for the ends of the flask which closure members have parts which are movable within the flask to compact the sand at the ends of the flask where the rims of the pipe are to be formed. However, previous proposals have not suggested a way of compacting the sand along the entire exposed surface of the sand mould and therefore over the areas where the sand has not been compacted the resultant pipe may well be of inaccurate dimensions.

It is the main object of this invention to provide a method and apparatus for forming a sand mould for the manufacture of a long pipe of, for example, between 6ft and 8ft in length which results in a more accurately formed pipe than has hitherto been possible.

According to the present invention there is provided a method of forming a sand mould for use in the manufacture of a pipe, including the steps of locating one end of a cylindrical flask against a sand blow head, moving a plate carrying a first socket forming sleeve and compacting ring so that the plate locates against the other end of the flask, feeding a cylindrical mandrel having an oversized head through an aperture in the plate until the head enters a second socket forming sleeve mounted on the blow head, blowing sand into the space so formed between the flask and mandrel, compacting the sand at each end of the flask by longitudinal movement of the compacting ring and second socket forming sleeve within the flask and withdrawing the mandrel so that the head thereof compacts and smooths the inner wall of the sand.

The invention also includes apparatus for forming a sand mould for use in the manufacture of a pipe, in-

cluding a cylindrical flask, a sand blow head, a plate movable towards and away from the blow head to clamp the flask therebetween, a first socket forming sleeve carried by the plate and positioned to enter the flask on clamping thereof, a compacting ring carried by the plate and capable of movement relative to the plate axially of the flask, a second socket forming sleeve mounted on the blow head and positioned to enter the flask on clamping thereof, said second socket forming sleeve being capable of movement relative to the blow head axially of the flask and an axially movable mandrel having an oversized head, said mandrel being movable within the flask from a position in which its head has entered the second socket forming sleeve to a position in which its head has entered the first socket forming sleeve.

Preferably, the blow head and plate are both provided with location means for accurately positioning the flask on clamping thereof.

Preferably, the mandrel passes through an aperture in the plate and the blow head is provided with means for accurately positioning the head of the mandrel in the second socket forming sleeve. Said means may include a projection on the blow head which enters a recess in the head of the mandrel for guiding the head of the mandrel to within the second socket forming sleeve.

Conveniently, the plate is slidably mounted and is moved by actuation of a first pair of piston and cylinder assemblies.

Preferably, the compacting ring is movable by actuation of a second pair of piston and cylinder assemblies which are mounted on the plate.

One embodiment of apparatus constructed in accordance with the present invention will now be described, by way of example only, and with reference to the accompanying drawings in which:

FIG. 1 is a side elevation of a flask within which a sand mould may be formed;

FIGS. 2A and 2B are part sectional side elevation views of apparatus according to the invention at the commencement of a mould forming cycle;

FIG. 3 is a cross-sectional view on the line III—III of FIG. 2B;

FIG. 4 is a view similar to FIG. 2 but with the apparatus in a position after the mould has been partially formed;

FIG. 5 is a fragmentary sectional view of part of the apparatus of FIG. 4 showing the blow head end of the flask before the sand is compacted;

FIG. 6 is a view similar to FIG. 5 but of the other end of the flask showing the position of the apparatus before the sand is compacted; and

FIG. 7 is a view similar to FIGS. 2 and 4 but showing the apparatus in a position in which the mould is being further formed.

In the drawings there is indicated a flask 1 of known construction which is cylindrical and of a length equal to the length of the cast iron pipe to be formed. The flask 1 is provided with a pair of spaced wheel members 2 which run on rails 3 mounted on a suitable form of base 4 so that the flask 1 may be conveyed through various stations of which the illustrated sand mould forming station is the first during the formation of a cast iron pipe. The construction of the remaining stations form no part of the present invention and therefore will not be described.

At the mould forming station illustrated in the drawings, there is provided flask feeding means generally indicated at 5 which is basically of known construction and enables the flask 1 to be fed axially towards or away from a sand blow head generally indicated at 6. The flask feeding means 5 includes a support structure 7 carrying a ram 8 which is capable of moving a flask support structure 9 slidably mounted by sliding bearings 10 on slide rods 11. The flask feeding means also includes a further ram 12 which moves a cradle means 13 on which the flask 1 is received and which discharges the flask after the sand mould has been formed. The provision of ram 8 at the mould forming station enables the flask 1 to be moved axially for the formation of the mould to commence.

At the mould forming station there is provided the sand blow head 6 previously mentioned which includes location means 14 which enables accurate location of one end of the flask 1 at the blow head. As will be seen from the drawing, the location means 14 is in the form of a ring having its inner peripheral edge chamfered at 15 for reception of one end of the flask 1. The location means 14 enables accurate location of one end of the flask 1 at the blow head 6.

Mounted on the blow head 6 is a socket forming sleeve 16 which has an external profile similar to the external profile of a socket end of the pipe to be formed. This socket forming sleeve 16 is movable axially of the flask 1 in relation to the blow head 6 by hydraulic or pneumatic pressure being applied to a chamber 17. The socket forming sleeve 16 may be spring returned or returned by the hydraulic or pneumatic pressure being applied to a return chamber.

The blow head 6 also includes a projection 18 which is tapered, the purpose of which will be described later. The blow head also includes blow holes 19 for blowing sand from a duct 20 into the flask 1.

At the other end of the flask 1 there is mounted a plate 21 slideable on rails 22 and movable axially of the flask 1 by a first pair of piston and cylinder assemblies 23. The rails 22 are mounted by brackets 24 on a supporting frame structure 25. The plate 21 is provided with location means 26 similar to the location means 14 at the blow head end for accurately locating the flask 1 at the plate end during clamping. The location means 26 is in the form of a ring having a chamfer 27 to assist in the location.

The plate 21 carries a socket forming sleeve 28 which has an external profile similar to the external profile of socket forming sleeve 16. The plate 21 also carries a compacting ring 29 which is movable in relation to the plate 21 and axially of the flask 1. The ring 29 is movable by actuation of a second pair of piston and cylinder assemblies 30 carried by the plate 21. The compacting ring 29 is connected to the second pair of piston and cylinder assemblies 30 by a yoke 31.

Passing through an aperture 32 in the plate 21 is a mandrel 33 with a head 34 which has an outside diameter greater than the diameter of the main length of the mandrel 33. Thus, the head 34 is oversized in relation to the mandrel. The mandrel 33 and head 34 are movable axially of the flask 1 by a single piston and cylinder assembly 35 which is supported by the main frame structure 25.

All of the piston and cylinder assemblies and rams mentioned above may be hydraulically operated.

To form a sand mould in accordance with the invention, the flask 1 is brought on rails 3 to the position illustrated in FIG. 2B. The flask 1 is then held in this position on track 3. The ram 8 is then actuated to move the flask 1 so that the blow head end thereof engages the location means 14 and by virtue of chamfered edge 15 thereof the blow head end of flask 1 is correctly located on the blow head as illustrated in FIG. 4. It will be noticed that when the flask is in position on the blow head the blow holes 19 provide communication from the sand duct 20 to within the flask 1.

The piston and cylinder assemblies 23 are then actuated and the plate 21 together with the socket forming sleeve 28 and compacting ring 29 are moved towards 15 the other end of the flask 1. This other end of the flask 1 engages the location means 26 and because of the chamfered edge 27 accurately locates the location means over the end of the flask 1. Thus, on clamping, the flask 1 will be in its correct position in relation to 20 the plate 21. The clamped position is illustrated in FIGS. 4 and 7.

The piston and cylinder assembly 35 is then actuated to feed the mandrel 33, together with its head 34, so that the head 34 locates within the socket forming 25 sleeve 16 as illustrated in FIG. 4. This location is achieved by the tapered configuration of projection 18 which engages within a recess within the head 34.

The flask is now located in position with the mandrel therein and between the flask and the mandrel there is 30 an annular space which receives sand to form the sand mould. Sand is blown via duct 20 through blow holes 19 into the space between the flask 1 and mandrel 33 to fill this space completely thereby compacting the sand and blow-forming a pipe mold. Thereafter, hydraulic pressure is applied to chamber 17 to move the socket forming sleeve axially inwardly of the flask and thereby compact the sand at the blow head end of the flask and form and consolidate this socket part of the mould. The position of the blow head end of the apparatus prior to the socket forming sleeve being moved is illustrated in FIG. 5 and after the socket forming sleeve has been moved the position is as illustrated in FIG. 4. It will thus be seen that movement of the socket forming sleeve compacts the sand in the area where the socket is to be formed on the pipe.

Simultaneously, the piston and cylinder assemblies 30 are actuated so that the compacting ring 29 will move axially inwardly of the flask 1 and compact the sand at the other end of the mould in the neighbourhood of the other socket. The position of the parts at this end of the flask prior to the compacting ring being moved are illustrated in FIG. 6 whereas after the compacting ring has been moved the position is as illustrated in FIG. 4.

The piston and cylinder assembly 35 is then reverse actuated to retract the mandrel 33 and its head 34 as illustrated in FIG. 7. The fact that the head 34 is oversized in relation to the mandrel 33 will mean that during this retraction the internal surface of the sand mould will be compacted and smoothed over its entire length by the head 34, apart from the sockets, and thus the entire internal surface of the sand mould will have been compacted, after the head 34 has travelled from the blow head end of the flask to lie within the first socket forming sleeve.

At this stage in the method, the sand mould has now been formed and the plate 21 may be retracted. The

flask will then be disengaged from the blow head 6 and the flask moved on rails 3 to a further station for further processing and eventually for use in the formation of a cast iron pipe.

A further flask will then be moved on rails 3 to the sand mould forming station and the method repeated for the formation of a further sand mould.

Various advantages accrue from the present invention, for example, a pipe mould is formed which is more accurate in its dimensions than previous moulds. This is brought about primarily by the positive clamping of the flask during the formation of the mould and the accurate positioning of the mandrel and its head. A further advantage is that the formed mould has increased hardness allowing for centrifugally casting heavy weight cast iron pipes without distortion or swelling in the mould.

I claim:

1. A method of forming a sand mould for use in the manufacture of a pipe, including the steps of locating one end of a cylindrical flask against a sand blow head, moving a plate carrying a first socket forming sleeve and compacting ring so that the plate locates against the other end of the flask, feeding a cylindrical mandrel having an oversized head through an aperture in the plate until the head enters a second socket forming sleeve mounted on the blow head, blowing sand into the space formed between the flask and mandrel thereby compacting the sand and blow-forming a pipe mold, compacting the sand at each end of the flask by longitudinal movement of the compacting ring and second socket forming sleeve within the flask, and withdrawing the mandrel from the second socket forming sleeve through the formed pipe mold and to the first socket forming sleeve while maintaining said plate with said first socket forming sleeve in place against said other end of the flask whereby said head further compacts and smoothes the inner wall of the sand of the pipe mold.

2. In apparatus for forming a sand mold for use in the manufacture of a pipe, a cylindrical flask within which sand is molded, a sand blow head for the injection of sand into said flask to form a pipe mold, means for causing relative movement between said flask and said sand blow head whereby the sand blow head is attached to and closes one end of said flask, a plate movable towards and away from said blow head to clamp said flask between said plate and said blow head and close the other end of said flask, a first socket forming sleeve carried by said plate and positioned to enter said flask on clamping thereof,

a compacting ring carried by said plate, means for moving said compacting ring relative to

said plate axially of said flask, a second socket forming sleeve mounted on said blow head and positioned to enter said flask on clamping thereof,

means for moving said second socket forming sleeve relative to said blow head axially of said flask for compacting sand in the flask,

a mandrel having an oversized head for compacting the inner wall of a sand mold, said mandrel being axially movable relative to said plate and said first socket forming sleeve, and

means for moving said mandrel within a pipe mold blow-formed in said flask from a position in which said enlarged head has entered said second socket forming sleeve to a position in which said enlarged head has entered said first socket forming sleeve while maintaining said plate against said other end of the flask whereby said enlarged head compacts and smoothes the inner wall of the sand of the pipe mold.

3. In apparatus according to claim 2, in which first and second location means are provided on said blow head and said plate respectively for accurately positioning said flask on clamping thereof.

4. In apparatus according to claim 3, in which both said first and said second location means are in the form of a ring having an inner peripheral edge chamfered for reception of said flask.

5. In apparatus according to claim 4, in which said mandrel passes through an aperture in said plate, and

means is provided on said blow head for accurately positioning said head of said mandrel in said second socket forming sleeve.

6. In apparatus according to claim 5, in which said means for accurately positioning the head of said mandrel in said second socket forming sleeve includes a projection on said blow head which enters a recess in said head of said mandrel for guiding said head of said mandrel to within said second socket forming sleeve.

7. In apparatus according to claim 2, in which there is provided

a first pair of piston and cylinder assemblies, and sliding means on which said plate is mounted, said plate being slidable on said sliding means by actuation of said first pair of piston and cylinder assemblies for moving said plate toward and away from said blow head.

8. In apparatus according to claim 2, in which there is provided

a second pair of piston and cylinder assemblies connected to said compacting ring for effecting movement thereof relative to said plate.

9. In apparatus according to claim 2, in which there is provided

a single piston and cylinder assembly connected to said mandrel and said enlarged head for effecting axial movement thereof.
